UNITED STATES PATENT OFFICE

143,951

DESIGN FOR A CHILD'S TRAINING TOILET SEAT

Sidney Cohen, New York, N. Y., assignor to Kiddie
Seat Corporation, New York, N. Y.

Application April 21, 1945, Serial No. 119,118

Term of patent 14 years

(Cl. D4—5)

To all whom it may concern:

Be it known that I, Sidney Cohen, a citizen of the United States and resident of the city and State of New York, county of Bronx, have invented a new, original, and ornamental Design for a Child's Training Toilet Seat, of which the following is a specification, reference being had to the accompanying drawings, forming part thereof.

Fig. 1 is a front elevation of a child's training toilet seat in unfolded condition, showing my new design.

Fig. 2 is a side elevation thereof.

Fig. 3 is a plan view and

Fig. 4 is a view similar to Fig. 3 showing the toilet seat in folded condition, the guard strap being omitted for convenience of illustration.

I claim:

The ornamental design for a child's training toilet seat, substantially as shown.

SIDNEY COHEN.
